UNITED STATES PATENT OFFICE.

J. NIXON BODINE AND OBERLIN SMITH, OF BRIDGETON, NEW JERSEY; SAID SMITH ASSIGNOR TO SAID BODINE.

DIRT-CART.

SPECIFICATION forming part of Letters Patent No. 329,703, dated November 3, 1885.

Application filed March 16, 1885. Serial No. 159,051. (No model.)

To all whom it may concern:

Be it known that we, J. NIXON BODINE and OBERLIN SMITH, citizens of the United States, residing at Bridgeton, in the county of Cumberland and State of New Jersey, have invented certain new and useful Improvements in Dirt-Carts, of which the following is a specification, reference being had therein to the accompanying drawings.

Figure 1 is a side view of our improved dirt-cart with the dirt-box in position for filling. Fig. 2 is a top or plan view of the same. Fig. 3 is a front view, the shafts being broken away. Fig. 4 is a partial view showing the dirt-box elevated for transportation. Fig. 5 is a partial view showing the dirt-box dumped. Fig. 6 is a vertical longitudinal section of the dirt-box. Fig. 7 is a transverse section of the same, taken on line $x x$, Fig. 6, looking in the direction of the arrow, Fig. 6. Figs. 8 and 9 are details. Fig. 10 is a detail, enlarged, on line $y y$, Fig. 1. Figs. 11, 12, and 13 illustrate in detail portions of the mechanism by which the dirt-box is elevated and lowered, Fig. 11 being a side view from the outside, Fig. 12 a similar view, parts being broken away, and Fig. 13 a top plan view.

Similar letters of reference indicate like parts in all the figures.

AA A' A² constitute a crank axle, the wheels B B being mounted on the parts A A of the axle, as is common in this class of machines.

C C are yokes or bracket-loops projecting upwardly and rearwardly from the vertical parts A' of the crank-axle, and c c are grooved wheels or pulleys pivoted in the yokes.

D D are the shafts or thills, secured at their rear ends to the crank-axle by any convenient or approved means, and D' D' are braces connecting the shafts with the upper part of the crank-axle.

E E is a disk or plate, preferably circular, and provided with a laterally-projecting tubular hub, (see particularly Fig. 10,) which has two chain-grooves, e e', and a ratchet-wheel, to be referred to. This flange and grooved sleeve or hollow hub are mounted loosely upon a tubular sleeve of a ratchet-wheel, G, (see particularly Fig. 10,) which in turn is mounted

upon one of the axle ends A, and is secured 50 to the spokes b of the carrying-wheel B by bolts, b', so as to rotate with said wheel.

F (see particularly Figs. 1, 2, and 8) is a locking-lever pivoted at f to the plate E, and provided with a jaw adapted to take into the 55 ratchet-wheel G.

Referring to Figs. 8 and 9, a clear understanding of the means for holding the jaw of lever F out of engagement with the teeth of wheel G may be had, Fig. 8 being a face view 6c of the ratchet-wheel G and the lever F, looking from the inside, plate E being removed, but its position indicated by dotted lines, and Fig. 9 being a sectional view on the line $x y$, Fig. 8.

e² e³ is a latch-loop, the longer arm e² of which is firmly attached to the plate E, and is provided at its upper end with a bent portion, to which is loosely connected the catch e³, the two parts, when in the position shown 70 in Fig. 9, forming a loop, in which lies the lever F. By moving catch e³ outward the lever F will be released and will fall until its jaw engages with a tooth on wheel G, when wheel G, lever F, and plate E will be locked 75 together until the lever is again released, in a manner to be described.

H is the dirt-box, open at its front edge and preferably shod with metal at that point, and having also a hinged door at its rear end for 80 the escape of the dirt. This rear end and the adjacent sides of the box should be provided with hooks or latches, as is customary in this class of machines.

H' H' are chains, each attached at its lower 85 end to the front end of the dirt box and at its upper end to a shaft, K, mounted upon the shafts or thills D of the cart, the shaft K being so constructed that the chains can be wound up upon it to regulate the position of 90 the front side of the dirt-box, so as to properly regulate the distance which the front edge of the dirt-box can fall below the shafts.

H² H² are chains, each attached at its lower end to the rear end of the dirt-box and at its 95 upper end to the crank-axle.

I I are slotted guides, one arranged at either end of the dirt-box and in a vertical or

slightly-inclined position. These guides are shown as being bolted at their upper ends to the crank-axle, and are also bolted about midway their heights to either the crank-axle, or 5 the shafts; so that they shall be rigidly supported.

J (see particularly Figs. 1, 3, 4, and 5) is a hanger sliding in one of the grooved guides, and having at its lower end a bearing in which 10 is mounted one of the gudgeons *j* of the dirt-box, one of the lifting-chains, J', being connected to the upper end of this guide J, and passing thence over the grooved pulleys *c c*, thence over the groove *e* in the sleeve or tubular bearing of the plate E, where it may be secured by a bolt similar to that shown at E', Fig. 10. The other lifting-chain, J', is attached at its lower end to the other gudgeon *j* of the dirt box, which projects through one 15 of the slotted guides, the upper end of this lifting-chain being attached to a bolt, E', in the groove *e'*. (See Fig. 10.)

M is a tripper projecting laterally from one of the upright parts, A', of the crank-axle, 20 (see Figs. 1, 2, and 3,) to engage with a corresponding laterally-projecting spur, f', on the lever F, as will be explained; or, if preferred, the tripper M may project from one of the slotted guides.

3c n is a pawl-lever pivoted to the crank-axle and taking into the ratchet-wheel N, which is formed integrally with or rigidly attached to the inner end of the sleeve of plate E.

O O are draft-chains, each attached at its 35 rear end to the dirt-box, preferably near a front upper corner, and adjustably connected with a loop or elongated eye, p, at the lower side of a plate or hanger, P, (see Figs. 1 and 2,) said hanger sliding upon a bar or way, Q, on the outer face of the thill or shaft D of the machine, there being, as indicated in Fig. 2, a device of this sort upon the outer face of each thill.

o is a hook attached to the front end of each 45 of the chains O, whereby the position of the hangers P relative to the front end of the dirt-box may be adjusted.

r is a hook projecting upward from the hanger P to receive one end of a chain which 50 runs over the saddle of the harness.

R is the chain attached to the hames or collar of the shaft-horse, and S is a chain running to the whiffletree of the lead-horse or helper, when one is used, there being similar 55 devices on both sides of the horse.

It will be seen that the latch L has two jaws, *l l'*, on its under surface, and is pivoted at *l'* to the inner face of the hanger J in an inclined position, so that its weight causes it to rest upon 60 the pin or stud *h*, which projects from the end of the dirt-box. There are similar locking-latches upon both sides of the dirt-box, with their substantially-horizontal handles or extensions projecting rearwardly toward the hinged side 65 of the box. From an examination of the drawings it will be seen that the distance between

these jaws *l l'* is such as to permit sufficient freedom of vibration of the box and allow it to properly engage with and scoop up the earth through which it is drawn, and will at 70 the same time maintain it in a horizontal or slightly-inclined position while it is being transported with its load of earth.

This dirt-cart may be operated as follows: The parts being in the position shown in Figs. 1 and 3, it is drawn forward, with its front edge resting upon and scooping up the earth, which has preferably been previously loosened by the use of a plow or pick. After sufficient earth has accumulated in the box the rear 80 end of lever F is released from the latch-loop *e' e'* and let down until the spur or tooth of the lever engages with the ratchet G. The horse or horses may then be started forward, when, the disk or plate E being connected with

the ratchet-wheel G by the lever F, the plate and its attached grooved hub or sleeve will rotate with the carrying-wheel B and wind up the lifting-chains, so as to elevate the dirt-box until the said plate and its grooved hub have made nearly one complete revolution, when the spur *f'* on the lever F will engage with the upper surface of the tripper M and throw the lever F into the position shown in Figs. 1 and 8, thereby disconnecting the plate F from 90 the ratchet G, so that the supporting-wheel can continue its rotation without further lifting the dirt-box. Of course the pawl of the lever *n* should be kept in engagement with the ratchet-wheel N, and thus support the dirt-box in its elevated position until it is transported to the place for lowering the body. By 95 preference, during this time of transportation, we so distribute the earth within the dirt-box, by means of hoes or other implement, that the box shall be tilted upon its gudgeons *j j*, as indicated in Fig. 4. By unlatching the latch L and unhooking or otherwise loosening the rear side of the dirt-box it will tilt and dump itself, as indicated in Fig. 5, and dump 100 the earth. The front side of the box is heavy enough under ordinary circumstances, by reason of its front edge being shod with metal, so that when tilted back with its front edge the lowest, as in Fig. 1, it will remain there; and when it is desired to lower the box this can be done by disengaging the pawl of lever *n* from the ratchet-wheel N, the lever being provided with a brake-shoe, *n'*, which may be made to engage with plate E when the lever 105 is disengaged from wheel N, and the chains are unwinding and the box being lowered, thus avoiding undue concussion, jarring, or wrenching of any of the parts.

We have found by experience that when the dirt-box is suspended from the shafts by chains or ties attached to the front side of the box, and running thence to the shafts under such arrangement as to length of chain that the front side of the box is supported positively, and cannot fall below a certain point relative to the shafts, the downward pull or thrust up-

on the front edge of the bottom of the box as it engages with the earth results in either bending the shafts downward, or pulling down so heavily upon the saddle or pad of the harness 5 of the horse or mule as to operate very injuriously; and to this end we have devised one part of our invention, which relates to a novel arrangement of draft-chains O O and their sliding hangers P P, whereby the draft of the 10 horse or horses is applied through the medium of the chains O O, instead of through the shafts, the gudgeons on the sides of the dirt-box, and the chains or ties which suspend the front side of the box from the shafts, as is done in an 15 earlier application, No. 132,284, of J. N. Bodine, filed May 21, 1884.

By an examination of these drawings it will be seen that the plates, runners, or hangers P are free to slide longitudinally relatively to 20 the shafts D, and that the length of the chains O O may be adjusted by means of the hooks o o, so that the draft of the horses is applied almost directly to the dirt-box, and at such an inclination relative to the surface of the ground 25 that in practice there will be very little, if any, downward thrust upon the front edge of the bottom board in excess of the upward pull or lift which is exerted by the chains O O, thus overcoming entirely the defect in operation 30 which has been above referred to as existing in carts of earlier construction.

We are aware that Patents No. 70,180 to Edson, and No. 82,295 to Day, show ratchet-wheels and brakes in winding up mechanisms 35 under a construction and arrangement of parts resembling ours in many respects, and hence do not claim anything shown in those patents; but our devices for rotating the grooved tubular hub and for supporting said hub differ 40 radically from anything shown in those earlier patents, as does also our construction of the lever n, its means for support, and the shoe which is attached to the lever and overhangs the grooved hub so as to engage with the circular plate E, which is at the end of the hub 45 opposite to that which has the ratchet-wheel N formed upon it.

We are aware that hangers or runners substantially such as shown at P, and similarly 50 mounted upon the bar Q, have been heretofore employed, but never, so far as we are aware, in combination with a dirt-box which is mounted upon pivots, so that its front edge or side can rise and fall, and is therefore subject to being forced in a downward direction 55 by being drawn through the soil which is to be excavated.

We do not wish to be limited to the exact construction and arrangement of hangers and 60 inclined chains O O which we have shown in the drawings, because many modifications will suggest themselves to skilled mechanics, but have described and illustrated the best construction and arrangement now known to 65 us for carrying out this part of our invention, which, of course, is applicable to dirt-carts in

which the appliances for raising and lowering, for supporting in an elevated position for transportation, and for dumping vary greatly from those which we have shown.

We do not wish to be limited to the exact form of winding mechanism which is represented by the plate E and its grooved sleeve mounted upon one of the axles of the supporting-wheels, because such winding mechanism 70 might be somewhat modified, or might be mounted upon the crank-axle or other part of the general frame-work of the machine and yet operate satisfactorily, and might be automatically thrown out of action whenever the 75 dirt-box has been lifted to a predetermined height. So, also, a winding mechanism constructed and arranged substantially as shown in the drawings might be used in connection with devices for connecting it with the supporting-wheel without any automatic 80 stopping mechanism, and yet be within the scope of our invention.

We are aware that it is old in self-loading carts to use a straight axle between the two 85 carrying-wheels, the lifting-chains from the scoop or dirt-box being wound thereon, or upon two sheaves or grooved pulleys carried thereby, as the axle is made to revolve by engagement with one of the wheels; and that 90 it is also old to employ, in combination with a cranked shaft situated between the wheels, a transverse shaft supporting two sheaves upon 95 which the lifting-chains are wound as the said shaft is intermittently made to revolve by 100 being brought into engagement with the wheels, and hence we disclaim such constructions; but we believe ourselves to be the first to employ, in a self-loading cart having a cranked axle so arranged that the dirt-box 105 may be elevated between the wheels and above the hubs thereof, a winding-up mechanism mounted directly upon the axis of the wheels and adapted to be brought into engagement 110 with the wheels intermittently, such construction permitting us to dispense with any supplemental shaft upon which to wind the chains, and also permitting us to elevate the dirt-box without causing the axle to revolve, the winding-up mechanism in our case being 115 mounted loosely upon the axle.

What we claim is—

1. In a dirt-cart, the combination, with a dirt-box, the supporting-wheels, an axle between the wheels, and lifting-chains, of a 120 winding-up mechanism mounted loosely upon the axle and means for intermittently connecting the winding-up mechanism with one of the supporting-wheels, whereby the dirt-box may be raised without rotating the axle, 125 substantially as set forth.

2. In a dirt-cart, the combination, with a dirt-box, the supporting-wheels, a cranked axle, and lifting-chains, of a winding-up mechanism mounted upon the axis of revolution 130 of the wheels and means for intermittently connecting the winding-up mechanism with

one of the supporting-wheels, whereby the dirt-box may be elevated above the hubs of the wheels, substantially as set forth.

3. In a dirt-cart, the combination, with a 5 dirt-box, the supporting-wheels, an axle between the wheels, and lifting-chains, of a winding-up mechanism mounted loosely upon the axle, means for intermittently connecting the winding-up mechanism with one of the 10 supporting-wheels, and mechanism, substantially such as described, for automatically disconnecting the winding-up mechanism from the supporting-wheel when the box has been elevated to a predetermined point, as set forth.

15 4. In a dirt-cart, the combination, with a dirt-box, the supporting-wheels, a cranked axle, and lifting-chains, of a winding-up mechanism mounted upon the axis of revolution of the wheels, means for intermittently connecting the winding-up mechanism with one 20 of the supporting-wheels, and mechanism, substantially such as described, for automatically disconnecting the winding-up mechanism from the supporting-wheel when the box has been elevated to a predetermined point, as set forth.

25 5. In a dirt-cart, the combination of a dirt-box, a winding-up mechanism mounted upon one of the axles, means for connecting the 30 winding-up mechanism with one of the supporting-wheels, a chain connected at its upper end to the winding-up mechanism and running thence down to the dirt-cart, and a chain connected at one end to the winding-up mechanism, running thence above the axles of the 35 supporting-wheels across the upper edges of the dirt-box, thence downwardly to the side of the dirt-box which is opposite to the winding-up mechanism, substantially as set forth.

40 6. In a dirt-cart, the combination, with the dirt-box and the lifting-chains, of the sleeve loosely mounted upon the axle and having one end of each chain attached thereto, a supporting-wheel loosely mounted upon the same axle, 45 a ratchet-wheel attached to and rotating with the supporting-wheel, and means for locking the supporting-wheel to the sleeve which has the chains attached thereto, substantially as set forth.

50 7. In a dirt-cart, the combination, with the dirt-box and the lifting-chains, of the ratchet-wheel G, provided with the sleeve mounted upon the axle, the supporting-wheel mounted upon the same sleeve and connected to the 55 ratchet, the disk E and its hub mounted loosely upon the sleeve of the ratchet-wheel, and means for connecting the plate with the ratchet-wheel, substantially as set forth.

8. In a dirt-cart, the combination of the 60 plate E, provided with a sleeve adapted to receive the lifting-chains, and with the ratchet-wheel N, the plate G, attached to and rotating with one of the supporting-wheels, and the pawls engaging with the ratchet-wheels G and N, substantially as set forth.

65 9. In a dirt-cart, the combination, with the

rising and falling hanger J, of the dirt-box pivoted in the lower end of the hanger, the latch-lever L, provided with the jaws l l' and pivoted at its upper end to the hanger above 70 the pivotal point of the dirt-box, and the stud h, affixed to the dirt-box and adapted to engage alternately with the jaws l l' of the latch-lever, substantially as set forth.

10. In a dirt-cart, the combination, with 75 the axle, the dirt-box, and the lifting-chains, of the disk E, provided with the tubular hub, chain-grooves, and ratchet-wheel N, the ratchet-wheel G, the locking-lever F, pivoted to the plate E, and the lever n, pivoted to the 80 crank-axle and provided with the brake projecting over the chain-grooves and engaging with the plate E, substantially as set forth.

11. In a dirt-cart, the combination, with 85 the plate E and ratchet G, of the lever F, pivoted to the plate E and adapted to engage with the ratchet G, and means for holding the lever out of engagement with the ratchet, substantially as set forth.

12. In a dirt-cart, the combination, with 90 the plate E and the ratchet G, of the lever F and means for automatically releasing the lever from engagement with the wheel at a predetermined point, substantially as set forth.

13. In a dirt-cart, the combination of supporting-wheels, a dirt-box, means for raising and lowering the dirt-box, and draft devices attached at their rear ends to the front side of the dirt-box and running thence in an upward and forward direction to the thills, and means for connecting the forward upper ends of the draft devices to the thills loosely, so that the draft devices may have a forward and backward movement independently of the thills, substantially as set forth.

14. In a dirt-cart, the combination of supporting-wheels, a dirt-box pivoted below the wheels, so that its front edge can rise and fall, and draft devices attached at their rear ends to the front side of the dirt-box and running thence forward and upward to the thills, and devices loosely connecting the upper forward ends of the draft devices to the thills, so that the draft devices can move forward and backward independently of the thills, substantially as set forth.

15. In a dirt-cart, the combination of supporting-wheels, a dirt-box pivoted between the wheels, draft devices attached at their rear ends to the front of the dirt-box and running thence upward and forward to the thills, supporting-chains H', attached at their lower ends to the front of the box and adjustably connected at their upper ends to the thills, whereby the inclination of the box and the depth to which it shall dig may be regulated, and means for locking the chains after adjustment, substantially as set forth.

16. In a dirt-cart, the combination of supporting-wheels, the dirt-box pivoted between 130 the wheels, the hangers P, the bars Q, and chains O, each chain attached at its rear end

to the dirt-box and at its front end adjustably connected to a hanger, P, substantially as set forth.

17. In a dirt-cart, the combination of the 5 supporting-wheels, the dirt-box pivoted between the wheels, the chains O O, the hangers P P, and the chains H', substantially as set forth.

18. In a dirt-cart, the combination of the 10 supporting-wheels, the dirt-box pivoted be-

tween the wheels, the hangers P P, the chains O O, the chains H' H', and the roller K, mounted upon the shafts, substantially as set forth.

In testimony whereof we affix our signatures in presence of two witnesses.
